REMOVABLE BUSHING

Leroy F. Hobert, Sandusky, Ohio, assignor to
The Universal Clay Products Co., Sandusky,
Ohio, a corporation of Ohio

Application May 5, 1939, Serial No. 271,930

5 Claims. (Cl. 16—2)

The present invention relates to removable bushings which are adapted to be inserted in openings in sign faces and similar walls. Such devices usually comprise an annular body of insulating material such as porcelain, the body having a flange on one side adapted to cover the opening and having an annular portion projecting through the opening. It is the principal purpose of the present invention to provide a device of this character with a clamping wire which is insertable through a keyhole type of opening and adapted to turn with the bushing so as to lock the bushing in place.

In devices of the type described it is a difficult matter to secure the bushing so that it will not be loose after it is mounted in place. My invention contemplates a clamping wire construction which is capable of holding the flange of the bushing firmly against the wall around the opening and which can be mounted from the outside of the sign casing without the use of any special tools.

The features and advantages of the present invention will appear more fully as the description proceeds, reference being had to the accompanying drawing wherein a preferred form of the invention is shown. It is to be understood, however, that the drawing and description are illustrative only, and are not to be taken as limiting the invention except insofar as it is limited by the claims.

In the drawing,

Fig. 1 is a view looking at the back side of a wall showing a bushing mounted in place;

Fig. 2 is a sectional view taken on the line 2—2 of Fig. 1;

Fig. 3 is an enlarged fragmentary sectional view showing the parts at the beginning of the mounting operation;

Fig. 4 is a sectional view taken on the line 4—4 of Fig. 3, and

Fig. 5 is a fragmentary sectional view taken on the line 5—5 of Fig. 3.

Referring now in detail to the drawing, the present invention is embodied in a porcelain bushing 10 and a clamping wire 11 by which the bushing is secured to a wall 12. These bushings are particularly applicable to installations where electrical devices pass through a metal wall and it is desired to close the space between the electrical device and the wall by means of an insulating material.

The invention is particularly applicable to the mounting of bushings in a sign face. It is, however, not so limited, as it may be applied where-

ever it is desirable to mount a flange element in a keyhole opening through a wall. By the term "keyhole opening", I mean an opening which is generally circular, such as the opening 13 shown in the wall 12, but which opening has a notch 14 in the periphery thereof.

The bushing 10 in the present instance comprises a flange portion 15 which is adapted to overlie the edge of the wall around the opening 13 and completely cover it. The bushing has a body portion 16 which is circular in shape and which is adapted to extend through the opening 13. The body portion 16 is provided with a groove 17 adjacent the flange portion 15. This groove 17 is shown as extending through the circumference of the bushing. This is not necessary, however, as will be readily appreciated. The groove 17 has its wall 18 bevelled or sloped outwardly away from the flange 15 for a purpose which will presently appear.

The bushing 10 is adapted to be secured in the opening 13 by the clamping wire 11. This wire is preferably a spring wire and is adapted to extend around the body portion 16 for more than one-half of its circumference. The resilient nature of the wire causes it to tend to move into the bottom of the groove 17, since it is originally bent to such a size as to place it under tension when it is mounted on the body portion 16.

The clamping wire 11 is shown as provided with three radially projecting portions 20, 21 and 22. The portion 20 is an end of the wire and lies in the plane of the clamping wire. The portions 21 and 22 comprise loops formed in the clamping wire and generally lying in the plane of the clamping wire. The loop 21 has a portion 23 which is curved away from the plane of the clamping wire. This portion 23 lies entirely on one side of the loop 21 so that the extreme outer tip 24 of the loop is in the plane of the clamping wire. A similar curved portion 25 is provided on the loop 22. The amount of curvature given to the portions 23 and 25 is sufficient to enable them to act as leading edges that will climb over the wall 12 in the manner illustrated in Figs. 3 and 4.

As seen in Fig. 3, the curved portion 23 is just beginning to overlap at the adjacent edge 26 of the wall 12. By continuing rotation of the bushing 10 and the clamping wire in the direction indicated by the arrow in Fig. 3, the loop 21 will be forced to climb over the wall 12. This will press the wall against the flange 15 and at the same time cause the clamping wire to be forced outwardly along the bevelled surface 18 of the groove 17.

17. As the bushing and wire are turned, the loop 22 will pass through the reduced portion 14 of the opening 13 and ride over the wall 12 in the same manner as loop 21. The projection 20 will then be forced out sufficiently to readily ride over the wall 12 when the projection reaches the opening 14. The spring tension of the clamping wire continuously acts to urge it into the bottom of the groove 17. The end projection 20 has a curved portion 20a which is like the portions 23 and 25 on the loops 21 and 22. This holds the flange portion 15 firmly against the wall 12 and prevents any rattling or looseness of the bushing in the wall.
- 15 From the foregoing description it is believed that the construction and operation of the present invention will be readily apparent to those skilled in this art. Having thus described my invention, what I claim as new and desire to 20 secure by Letters Patent is:
1. A removable bushing of the character described having a flange portion adapted to cover the edge around a keyhole opening in a wall, said bushing having a body portion substantially 25 smaller than said flange portion and adapted to pass through the aforesaid opening, the periphery of said body portion having a groove to receive a clamping wire, and a clamping wire around said body portion, said wire having radially projecting 30 portions which terminate short of the periphery of said flange portion of the bushing, one of said radially projecting portions comprising a loop in the plane of the clamping wire, said loop having a portion of one side turned out of the 35 plane of the clamping wire intermediate its ends, whereby to provide a leading edge that will ride over the edge of said keyhole opening.
2. A removable bushing of the character described having a flange portion adapted to cover 40 the edge around a keyhole opening in a wall, said bushing having a body portion substantially smaller than said flange portion and adapted to pass through the aforesaid opening, the periphery of said body portion having a groove to receive a clamping wire, and a clamping wire around said 45 body portion, said wire having radially projecting portions which terminate short of the periphery of said flange portion of the bushing, one of said radially projecting portions comprising a loop in the plane of the clamping wire, said loop having

a portion of one side turned out of the plane of the clamping wire intermediate its ends, whereby to provide a leading edge that will ride over the edge of said keyhole opening, the wall of said groove which faces the flange portion being 5 bevelled.

3. A removable bushing of the character described having a flange portion adapted to cover the edge around a keyhole opening in a wall, said bushing having a body portion substantially 10 smaller than said flange portion and adapted to pass through the aforesaid opening, the periphery of said body portion having a groove to receive a clamping wire, and a spring clamping wire under tension around said body portion, said wire 15 having radially projecting portions which terminate short of the periphery of said flange portion of the bushing, one of said radially projecting portions comprising a loop in the plane of the clamping wire, said loop having a portion of 20 one side turned out of the plane of the clamping wire intermediate its ends, whereby to provide a leading edge that will ride over the edge of said keyhole opening, the wall of said groove which faces the flange portion being bevelled. 25

4. A device of the character described adapted for mounting in a keyhole opening in a wall, said device comprising a body portion adapted to pass through said opening, a flange portion thereon adapted to cover said opening, said body portion 30 having a groove in the periphery thereof, a spring wire in said groove, said wire having a radially projecting loop one side of which is turned up intermediate its ends whereby to provide a leading edge that will ride over the edge of said keyhole opening. 35

5. A device of the character described adapted for mounting in a keyhole opening in a wall, said device comprising a body portion adapted to pass through said opening, a flange portion thereon adapted to cover said opening, said body portion 40 having a groove in the periphery thereof, a spring wire in said groove, said wire having a radially projecting loop one side of which is turned up intermediate its ends whereby to provide a leading edge that will ride over the edge of said keyhole opening, the wall of said groove which faces the flange portion being bevelled. 45
